DESIGN FOR A DISPLAY CONTAINER FOR JEWELRY OR SIMILAR ARTICLES

John B. Guttman, Brooklyn, N. Y., assignor to Jacob J. Schmukler and Bernard M. Schmuk-ler, co-partners doing business as J. J. Schmuk-ler & Son

Application October 7, 1937, Serial No. 72,037

Term of patent 3½ years

To all whom it may concern:

Be it known that I, John B. Guttman, a citizen of the United States, residing at Brooklyn,
New York city, in the county of Kings and State of New York, have invented a new, original, and ornamental Design for a Display Container for Jewelry or Similar Articles, of which the following is a specification, reference being had to the accompanying drawing, forming a part thereof.

Fig. 1 is a perspective view of a display container for jewelry, showing my new design, with the cover in open position.

Fig. 2 is a top plan view of the same, with the cover in closed position.

Fig. 3 is a side elevational view thereof, with the cover in open position on a reduced scale.

Fig. 4 is a rear elevational view thereof, with the cover in closed position on a reduced scale.

Fig. 5 is a sectional view thereof, taken on the line 5—5 of Fig. 1, with the cover in closed position on a reduced scale.

I claim:

The ornamental design for a display container
for jewelry or similar articles, as shown.

JOHN B. GUTTMAN.
